[57] CLAIM

The ornamental design for a corner structure for shelving, substantially as shown.

DESCRIPTION

FIG. 1 is a perspective view of a corner structure for shelving showing our new design;

FIG. 2 is a top plan view thereof;

FIG. 3 is a front elevational view thereof;

FIG. 4 is a left side elevational view thereof;

FIG. 5 is a rear elevational view thereof;

FIG. 6 is a bottom plan view thereof; and

FIG. 7 is a sectional view taken along line 7-7 of FIG. 5.
